UNITED STATES PATENT OFFICE.

JOHN A. DIENNER, OF CHICAGO, ILLINOIS.

DICTAPHONE MANDREL.

Application filed May 18, 1921. Serial No. 470,587.

My invention relates to mandrels, particularly of the class such as are employed in holding the cylindrical wax record of talking machines, such as are known under the 5 trade name of dictaphone.

I have observed in the operation of these machines that the removal of the cylinder from the mandrel is attended with considerable inconvenience due to the fact that means 10 has heretofore been provided, requiring one hand to operate for shoving the cylindrical record off of the mandrel, and the other hand has been required to receive the cylinder as it is so being shoved off.

15 The object of my invention is to provide a device such that by the simple manipulation of one hand the cylinder may be forced off of the mandrel, and may be received by the hand which performs this operation.

20 Other and incidental objects of my invention will be apparent from the following description.

In the accompanying drawings, forming a part of the present specification, I have 25 illustrated an embodiment of my invention.

Figure 1 is a longitudinal axial section of a device embodying my invention; and

Figure 2 is an end view thereof.

The mandrel 1 may be made of any suitable material, either solid or hollow for receiving the wax cylinder 2 upon which the record is made. The mandrel 1 is supported upon and driven through a shaft 3 which is secured to the mandrel in any convenient 35 or well known manner. The mandrel is preferably provided with a flange 4 which limits the axial movement of the blank inwardly into place, and is provided with spring pressed plates or lands 5 which tend to center the cylinder and hold the same with a suitable degree of friction upon the mandrel.

Disposed on the outer end of the mandrel, I provide means in the form of a plate or 45 button 6, which is connected through a rod or shaft 7 with a pair of lever arms 8-9 pivoted in the mandrel at 10-11 and having their inner ends connected to the shaft or rod 7 by a slotted cross piece 12. The cross 50 piece 12 is slotted in order to receive the pins 13-14, which are connected to the ends of the inner arms of the levers 8 and 9.

A spring 16 is provided in the mandrel for normally withdrawing the levers 8 and 55 9 from contact with the cylinder 2.

The spring pressed plates 5 are formed of sheet metal, folded into U-shape as is indicated in Figure 2, and these pieces are prevented from coming out of the opening in which they are set by extending end pieces 60 17 as is clear from Figure 1.

The operation of the device is as follows:

The cylinder is picked up in the usual manner by inserting the fingers on the inside of the same, and is then placed upon the 65 mandrel and the fingers are removed while the cylinder is shoved with the flat of the hand upon the mandrel. The cylinder may then be scribed in the well known manner, and when it is desired to remove the cylinder from the mandrel, the needle is raised from the cylinder, and with the second and third fingers of the right hand, the operator presses upon the plate or button 6, whereupon the levers 8 and 9 are caused to push 70 upon the inner end of the cylinder, pushing it for a short way off of the mandrel, so that the fingers of the hand may be free to pull the cylinder off of the mandrel. It is to be noted that the mandrel is made with 75 a slight taper, so that as soon as the cylinder is started for a short distance off of the mandrel, the cylinder will come off the rest of the way quite easily.

I believe that I am the first to provide a 80 member on the mandrel itself for removing the wax cylinder.

I do not intend to be limited to the precise construction shown:

I claim:

1. In a sound recording and reproducing machine, the combination with a sound record cylinder of a tapered mandrel adapted to support and rotate said record cylinder and pivoted members whereby said record cylinder may be moved longitudinally towards the small end of said mandrel, and means disposed co-axially of the mandrel and movable relative to the mandrel for effecting the operation of the pivoted members.

2. In a sound recording and reproducing machine the combination with a sound record cylinder of a tapered mandrel adapted to support and rotate said record cylinder and pivoted members whereby said record cylinder may be moved longitudinally towards the small end of said mandrel, and means disposed coaxially of the mandrel for effecting the operation of the pivoted 105 110 members.

- members, said coaxial means having a button at the small end of the mandrel and movable relative to the mandrel adapted to be struck by the fingers of the operator to project the cylinder out over said fingers, said button being normally substantially flush with the end of the cylinder and movable inwardly relative to the cylinder as the cylinder is ejected outwardly over the fingers of the operator.
3. In combination, a mandrel adapted to receive a cylinder, a lever pivoted at the inner end of the mandrel for engaging the inner end of the cylinder, and means extending through the outer end of the mandrel and lying inside of the mandrel for operating said lever.
4. In combination, a tapered mandrel for receiving a cylinder, a swinging lever carried by the mandrel for engaging the inner end of the cylinder to force the same off the mandrel, and a slidable rod axially disposed in the cylinder and extending to the outer end of the cylinder.
5. In combination, a tapered cylinder receiving mandrel, a push plate at the small end of the mandrel engageable by the fingers of the hand of the operator, said push plate being movable with respect to the mandrel, and means actuated by the push plate for throwing the cylinder outwardly a sufficient distance to embrace the fingers which engage the plate.
6. In combination, a relatively stationary mandrel for supporting a cylinder, a relatively movable push rod mounted on the mandrel, and means mounted on the mandrel and connected to the push rod for shifting the cylinder axially toward the end of the mandrel.
7. In combination, a relatively stationary tapered mandrel, resilient engaging means mounted on the mandrel for engaging and frictionally holding a cylinder, a finger piece at the small end of the mandrel, stripping means at the larger end of the mandrel, and means mounted on the mandrel and movable with respect thereto connecting said finger piece and said stripping member.
8. In combination, a tapered mandrel having resilient cylinder engaging members for frictionally holding a cylinder, said mandrel being held against axial motion, stripping means at the inner end of the mandrel, and means extending from the outer end of the mandrel to said stripping means and axially movable with respect to said mandrel for actuating said stripping means to push the cylinder along the mandrel to free it from said frictional holding means.
9. In combination, a mandrel for supporting a cylinder said mandrel being held against axial motion, and movable means mounted on the mandrel for stripping the cylinder from the mandrel, said means having a finger piece lying at one end of the mandrel and being axially movable towards the other end of the mandrel to strip the cylinder from the mandrel in the opposite direction.
10. In combination, a tapered mandrel held against axial motion, a shaft supporting one end of the mandrel, a finger piece at the opposite end of the mandrel, and stripping means lying at the larger end of the mandrel and being connected to the finger piece for projecting the cylinder over the fingers of the operator when the finger piece is pushed axially with respect to the mandrel.
11. In combination, a tapered cylinder receiving mandrel adapted to receive a cylinder, means at the large end of the mandrel for pushing the cylinder out over the small end of the mandrel, and a push plate at the small end of the mandrel and connected to said cylinder pushing means and adapted to be engaged by the fingers of the operator, said push plate being disposed substantially flush with the end of the cylinder when the cylinder is in place upon the mandrel and moving inwardly as the cylinder is pushed outwardly to carry the fingers of the operator inside the cylinder as the cylinder is pushed from the mandrel.
12. In combination, a mandrel for supporting a cylinder along substantially its full length, stripping means for engaging the inner end of the cylinder to disengage the cylinder from the mandrel, actuating means at the outer end of the mandrel adapted to be engaged by the fingers of the operator, and to be carried axially within the end of the cylinder, so that the cylinder when released embraces the fingers of the operator which engage the actuating means.
- In witness whereof, I hereunto subscribe my name this 12 day of May, 1921.

JOHN A. DIENNER.
